UNITED STATES PATENT OFFICE.

DAVIS RATCLIFF, OF GLOSTER, MISSISSIPPI.

RAIL-JOINT.

1,109,465.

Specification of Letters Patent. Patented Sept. 1, 1914.

Application filed August 16, 1911, Serial No. 644,324. Renewed February 2, 1914. Serial No. 816,091.

To all whom it may concern:

Be it known that I, DAVIS RATCLIFF, a citizen of the United States, residing at Gloster, in the county of Amite and State of Mississippi, have invented new and useful 5 Improvements in Rail-Joints, of which the following is a specification.

The invention relates to railway rails, and more particularly to the class of rail joints 10 known as "scarf joints."

The primary object of the invention is the provision of a rail joint in which the meeting ends of railway rails may be expeditiously united with each other, as the same 15 are placed upon the road-bed or ties, and that will be prevented from separation, or the balls of the rails lowering with respect to each other, thereby avoiding the pounding of car wheels when passing over the 20 joint.

Another object of the invention is the provision of a rail joint, in which the meeting ends of rails may be readily and easily fastened together, so as to avoid lateral displacement of such meeting ends, and also 25 prevent the sagging of one rail with respect to the other.

A further object of the invention is the provision of a rail joint which is simple in 30 construction, efficient in its purpose, and enabling the rails to be manufactured at a minimum expense.

With these and other objects in view, the invention consists in the construction, combination and arrangement of parts, as will be hereinafter more fully described, illustrated in the accompanying drawings, and pointed out in the claims hereunto appended.

In the drawings: Figure 1 is a side elevation 40 of a rail joint constructed in accordance with the invention. Fig. 2 is a similar view showing the rails separated. Fig. 3 is a perspective view of one rail end, the other rail end being detached therefrom. Fig. 4 is a perspective view of the other rail end. Fig. 5 is a sectional view on the line 5—5 of Fig. 1. Fig. 6 is a sectional view on the line 6—6 of Fig. 1.

Similar reference characters indicate corresponding parts throughout the several views of the drawings.

Referring to the drawings by numerals, 5 and 6 designate the meeting ends of railway rails which are of the usual well-known construction, except as to their joints, the 55 said rails being spiked in the usual manner

to the ties 7. However, the rails may be superimposed upon any suitably prepared road-bed, if desired. The adjoining ends of the rails 5 and 6 are provided with thickened webs 8, so as to provide for the special shape and construction of said ends, presently described. The rails 5 and 6, at the base flanges and balls or treads thereof, are diagonally cut or severed at reverse angles to 65 form beveled abutment faces 9 and 10, respectively, while the thickened web 8 of the rail 5 is formed with beveled or inclined shoulders 11 at opposite sides of a medial inclined locking tongue 12, the latter being 70 adapted to fit in a correspondingly shaped socket or recess 13 formed in the thickened web 8 of the rail 6, the said thickened portion being provided with beveled surfaces 14 at opposite sides of the groove or recess 75 13, so as to engage the beveled shoulders 11 when the tongue 12 of the rail 5 is fitted within the recess or groove 13 in the rail 6 for the joining thereof.

Formed on the under face of the projected portions of the ball of the rail 6 is a depending locking lug 15, the latter being adapted to engage in a correspondingly shaped socket 16 formed in the upper face of the thickened web 8 rearwardly of the 85 tongue 12. The lug 15, when engaged in the socket 16, will prevent the separation of the rail ends, as will be clearly obvious.

Formed in the tongue 12 is a suitable bolt receiving opening 17 which is adapted to 90 align or register with similar bolt receiving openings 18 formed in the thickened web 8 of the rail 6, and intersecting the recess 16 therein, and adapted to be inserted in these openings 17 and 18, when in alignment 95 with each other, is a bolt member 19, thereby securely fastening the meeting ends of the rails together.

In the construction of a rail joint, as heretofore described, it is unnecessary to use 100 fish plates or a plurality of bolt members for securing the meeting ends of the rails together, and there will be no possibility of the rails becoming loose or detached from each other, nor will the balls or treads of 105 the rails sag or lower with respect to each other. Furthermore, the rail ends will be prevented from any lateral displacement or separation.

What is claimed is:

1. In a rail joint, a pair of rail ends having their base flanges and balls provided

with reversely beveled abutment faces spaced from each other, respectively, the webs of the said rail ends being provided with inclined surfaces, one of said webs being provided with a recess, a tongue formed on the inclined surface of the web of the other rail and engageable in the recess, a bolt member passed through the tongue and adjacent walls of the recess receiving the same for locking the rail ends together, one of said rail ends being provided with a socket, and a depending locking lug on the other rail end for engagement in the socket to hold the rail ends joined.

2. In a rail joint, a pair of rail ends, each having its ball and base reversely beveled and its web thickened, one of said webs being provided with a medial groove in its free edge, a tongue projecting medially from

the other web and engageable in said groove, 20 the ball of one rail being extended beyond the web, the ball of the other rail being retracted from the free edge of its web, whereby on the joining of the webs of the rails the projected portion of the ball of one rail 25 will overlie the web of the other rail, a lug depending from the projected portion of the ball of one rail and engageable with the underlying web of the other rail, and a bolt member passed through the side walls of the 30 groove in one web and engageable in the tongue on the other web.

In testimony whereof I affix my signature in presence of two witnesses.

DAVIS RATCLIFF.

Witnesses:

O. E. LUSK,
HY. BURKE.
